BABY SLEEPER

Robert Widetsky, Los Angeles, Calif., assignor, by
mesne assignments, to Sam G. Kaplan and Rose
Ruth Kaplan, doing business as Ronny Mfg.
Co., Los Angeles, Calif.

Application July 19, 1947, Serial No. 762,024

7 Claims. (Cl. 128—134)

1

The present invention relates to garments for babies in general and particularly to a sleeper in which the baby can be placed and comfortably secured while in a crib.

The technique of caring for infants has made important advances within the last generation. Clothes and accessories have been designed for the living of babies as well as for adults and as a result the burdens and care of the mother have been materially lightened. The advantages and desirability of the child's accessory which may properly be called a baby sleeper can perhaps be best understood by reciting certain problems which arise in child care. Following its bath the body is dried, put into its nightgown and wrapped in one or more blankets to prevent catching cold, and either put to bed with its bottle or given its bottle before being placed in its crib. In either event it is essential that following the bath it be kept warm and out of drafts, and that when placed in its crib it shall remain covered and securely held against displacement relative to its covers which might possibly result in strangulation, in becoming uncovered, or in falling from its crib. The sleeper constructed in accordance with the present invention is particularly designed to insure that the baby will at all times be protected and will remain covered after being positioned therein.

It is an object of the present invention to provide a new and improved baby sleeper.

It is another object of the invention to provide a new and improved baby sleeper in which the child may be positioned and carried about as desired or securely fixed in its sleeping crib.

A further object of the invention is to provide a combination garment comprising a first part removably secured to the child's crib and a second part in which the child is positioned which is removably secured to the first part.

These and other more specific objects will appear upon reading the following specification and claims and upon considering in connection therewith the attached drawing to which they relate.

Referring now to the drawing in which a preferred embodiment of the invention is illustrated:

Figure 1 is a view in perspective of the baby sleeper constructed in accordance with the present invention;

Figure 2 is a partial section upon the line 2—2 of Figure 1 showing the connecting means comprising a slide fastener by which the child-enclosing element or nest is removably secured to the crib-secured element;

Figure 3 is a partial section looking in the di-

2

rection of the arrows upon line 3—3 of Figure 1 through the shoulder portion of the child-enclosing element;

Figure 4 is a partial section upon the line 4—4 of Figure 1 and discloses the construction of the end of the sleeve; and

Figure 5 is a view in perspective of the child-enclosing unit or nest removed from the crib-secured unit or nest and opened ready to receive the infant.

Referring again to the drawing in which a preferred embodiment of the invention is illustrated, a baby sleeper constructed in accordance with the present invention is indicated generally by the reference character 10 and is seen to comprise two principal parts; a crib-secured element or sheet 11 having top and lower surfaces and a body-enclosing element or nest 12 having top and lower surfaces. Referring first to element 11, it is seen to comprise a flat sheet of material, preferably made of strong fabric which, in the preferred form illustrated, although this is not necessarily the case, is rectangular. Sheet 11 is provided at spaced points along its sides, and preferably at its corners, with securing straps 13 which may also be of fabric. Element 11 is cut out at one side in the form of an arcuate sector 14, one side 16a of a slide fastener being secured thereto.

Referring now to the removable element 12, that member is seen to comprise a lower portion 17 shaped to conform to the cut-out arcuate curve 14 in the member 11, a central body portion 18, a shoulder portion 19, and arm portions 21. Lower portion 17 comprises merely a flap and carries the cooperating side 16b of the slide fastener 16 which enables it to be secured detachably to the element 11. The portions 18, 19 and 21, however, are provided with a back, indicated generally by the reference character 22, which back conforms exactly to their outlines and cooperates therewith to form a child's jacket which may be referred to as a nest. The body portion 18 is divided centrally from a neck 23 cut out of the shoulder portions 19, the opening normally being closed by a slide fastener 24, including a movable slide 26. If desired a snap fastener 27 may be provided at the neck end of the opening to prevent the slide from accidentally opening.

The outer ends of the arm portions 21 are slotted along their upper surfaces, as indicated at 31, the sides of the slot extending in overlapping relationship to provide an opening through which the hands of the child can extend when desired.

In the use of the sleeper constructed in accordance with the present invention the cover element 11 is secured to the child's crib or suitable supporting surface by the straps 13. It being desired to prepare the child for bed, as for example after a bath, the child is placed in the nest through the central opening of the body portion 18 and the opening closed by the zipper 24 so that the child's head extends above the shoulder portions 19 with his arms extended into the arm portions 21. The lower portion or flap 17 can be wrapped around the child's legs and both he and the nest can be bundled in blankets if desired, as during a nursing period. It being decided that the child should be put to bed, the encircling wrappings, such as blankets are removed and the child is placed with his feet in the cut-out arcuate portion 14 of the cover 11. The flap portion 17 of the nest is then fitted to the cut-out section and the zipper 16 closed by the movement of the slide 15. As is illustrated most clearly in Figure 2, the cover 11 overlaps the adjacent surface of the flap 17 and the zipper 16 is entirely concealed from view. So long as the zipper 24 remains closed the child cannot become displaced from the unit, the neck piece 23 encircling his neck and being too small for his head to pass through. If desired the child's hands can extend through the openings 31 at the end of the arm portions 21, as may be desirable in hot weather.

To remove the child substantially the reverse operation is followed although, if desired, the nest 12 can be left in place and the child removed merely by opening the slide fastener 24.

It is to be understood that the exact shape of the nest 12, and particularly its flap 17, is not of the essence and that it is the cooperative relationship between the nest and the cover 11 which is of primary importance.

While the particular construction herein shown and described in detail is fully capable of attaining the objects and providing the advantages hereinbefore stated, it is to be understood that it is merely illustrative of the presently preferred embodiment of the invention and that no limitations are intended to the details of construction or design herein shown other than as defined in the appended claims.

I claim:

1. A baby's sleeper comprising a cover including means by which it may be secured to a crib and being cut out on one side, and a nest including a baby-encircling portion, a portion to fit the cut-out side of said cover, and cooperating means to secure said nest and cover detachably.

2. A baby's sleeper comprising: a cover cut out on one side and including means by which it may be secured removably to a crib; and a nest including a baby's jacket with a body portion and arms, a flap connected to said jacket and contoured to fit the cut-out side of said cover; and cooperating means on said cover and flap to secure said cover and nest detachably.

3. The construction set forth in claim 2 characterized in that said flap supplements said cut-out cover to form a continuous sheet and in that the remainder of said nest is positioned beyond the marginal limits of said cover.

4. The construction set forth in claim 2 characterized in that in the assembled relationship of said cover and nest the cover, flap and the top surface of said jacket form a continuous top surface below a portion of which is positioned the bottom surface of said jacket.

5. The construction set forth in claim 2 characterized in that said arms are closed at their ends and are formed with hand slots in their upper surfaces.

6. The construction set forth in claim 3 characterized in that said flap is of greater width than said jacket and is adapted to be wrapped around the lower limbs of a baby positioned in said jacket.

7. The construction set forth in claim 4 characterized in that said jacket is provided with an opening normally closed by a slide fastener and through which a baby can be positioned without disconnecting said flap and said cover.

ROBERT WIDETSKY.
